UNITED STATES PATENT OFFICE.

GUSTAVUS W. SCHUESSLER, OF MASON, TEXAS.

TELEPHONE-SIGNAL.

No. 840,589.

Specification of Letters Patent.

Patented Jan. 8, 1907.

Application filed September 23, 1905. Serial No. 279,866.

To all whom it may concern:

Be it known that I, GUSTAVUS W. SCHUESSLER, a citizen of the United States, residing at Mason, in the county of Mason and State of Texas, have invented a new and useful Telephone-Signal; and I do hereby declare the following to be a full, clear, and exact description of the invention, such as will enable others skilled in the art to which it appertains to make and use the same.

This invention relates to certain new and useful improvements in a switchboard-drop of the visual signal for magneto system at the central office of a telephone company; and, more particularly, the invention consists in the provision of a device, as hereinafter described, claimed, and shown in the accompanying drawings, which may be easily adapted in connection with a suitable switchboard of a magneto system.

Another object of the invention is to provide a device of this character whereby as a telephone call is made the armature and indicator is locked in the vision of the switchboard operator, and by inserting the plug of the telephone-number which is called into the socket of the device it will absolutely restore the indicator and armature to its normal position entirely by gravitation, thereby making the device very efficient and durable and at the same time obviating springs which become non-serviceable.

The invention, as shown, is adapted for grounded systems; but it is to be distinctly understood that the invention is not to be limited to any particular system, but may be adapted in connection with a metallic system as well.

The invention comprises further objects and combinations of elements, which will be hereinafter set forth, and the novel features thereof will be referred to by the appended claims.

To obtain a full and correct understanding of the details of construction and combinations of features, elements, and advantages, reference is to be had to the hereinafter set forth description, in connection with the accompanying drawings, wherein—

Figure 1 is a perspective view of the improved switchboard-drop, showing in a diagrammatic way the relative electrical connections of the operative elements. Fig. 2 is a longitudinal sectional view through the switchboard-drop with the plug inserted within the socket. Fig. 3 is a diagrammatic view

of the electric wiring of the switchboard-drop. Fig. 4 is a cross-section on the line 4-4 of Fig. 2, and Fig. 5 is a detail perspective view of the armature and indicator.

Making renewed reference to the drawings, wherein similar reference characters indicate corresponding parts in the several illustrations by figures, 1 designates the base of the switchboard, which is made of suitable insulated material, upon one end of which is a suitable standard 2, which carries an electromagnet 3, which is adapted to attract an armature 4, which is pivotally mounted at one end of said magnet when a telephone call is made and at the same time closing the night-bell circuit, as hereinafter described.

The armature is made integral with the weighted indicator-rod 5, having an indicator-plate 6 at one end thereof, which is provided with a suitable telephone-number which designates a telephone to which the switchboard is electrically connected. The indicator-rod is adapted to coöperate with the notch 7 of a vertically-oscillating releasing-bar 8, which is mounted upon the core of said magnet, as illustrated in the accompanying drawings. The weighted lower end 9 of said releasing-bar 8 is adapted to coöperate with the cut-away portion 10 of the socket member 11 of the device. The said lower end 9 of the releasing-bar 8 only lies within the cut-away portion when the armature is attracted, which causes the indicator-rod to be thrown into engagement with the notch 7 of said bar.

There are two metallic strips 14 and 15 provided upon the under side of the base of the device, said strips being insulated from one another by suitable insulating material. Said strips also form an electrical connection when a telephone-number is desired, which causes the armature to be attracted, and the longest strip 15 makes an electrical connection with the telephone that is called when the plug 13 is inserted within the socket 11 and at the same time cuts out the magnet by separating the plane surface of the strip 15 from the contact-point 16 of the strip 14, as clearly shown in the drawings.

The operation of the device is set forth as follows: As the receiver 17 of the telephone 18 is lifted from the holder at the subscriber's telephone 18, thus permitting a current of electricity to flow from the battery 19 through the wire 20 to a binding-post 21 of the switchboard, then from said binding-

post 21 through the strip 15, through the contact-point 18, then through the strip 14, and through the wire connection 22 between said strip 14 and the magnet 3. The said magnet thus energized causes the armature to be attracted, which throws the indicator into the vision of the operator and also coöperating with the notch 7 of the oscillating bar 8, as hereinbefore specified. The current then flows from the magnet through the wire connection 23 between said magnet and the binding-post 24, opposite the binding-post 21, then through the wire 25 and through the ground, as at 26 and 27, and through the wire 28 to the telephone 18 and back to the battery 19; thus completing the circuit for notifying the operator of a telephone call. Before a call is made the normal position of the indicator is, as shown in Fig. 2, without the plug in the socket. After the call is made the indicator is raised. The plug 13 is then inserted within the socket 11, which restores the indicator and armature to their normal positions through the coöperation of the oscillating bar 8 with the plug 13 and the indicator-rod. The current is then carried from the battery 19 to the binding-post 21 through the wire 20 and from said binding-post 21 through the strip 15 and through the plug 13, from which it is carried through the wire 29 to the battery 30 and through the wire 31 to the telephone 32 which is desired by the one who wishes to talk therethrough. The current is then carried to and through the ground, as at 26 and 27, by the wire 33 and then back to the battery 19 through the wire 28 to the telephone 18; thus completing the circuit after the telephone 32 has been placed in connection therewith, as clearly illustrated in Fig. 1 of the accompanying drawings. This last description of the flow of current absolutely cuts the magnet out of circuit, as will be readily understood from reference to the accompanying drawings.

45 A night-bell circuit is utilized when desired and is set forth as follows: When the indicator is thrown into the vision of the operator, as herein described, the spring 12 forms contact with the indicator-rod 5, which closes the circuit through the medium of the wires 35 and 36, the battery 37, the night-bell 38, and the wire 39. When the plug 13 of the telephone 32 is inserted in the socket 11, the contact of the spring with the indicator-rod is broken, which will cause the night-bell to stop ringing and also close the circuit between the subscriber's telephone 18 and the telephone 32, as clearly illustrated in the accompanying drawings. This same circuit is also to be used in the day-time with a relay 40 in the circuit that is connected by the wires 41 and 42, and which relay is operated by the battery 37, whereby as the indicator makes its appearance the indicator-rod, 60 thus closing the circuit, gives one tap of the

bell 44, which notifies the operator that the call has been made should the operator not be looking at the switchboard, and by reversing the switch 43 at night, as clearly shown in full lines in Fig. 1 of the drawings, it connects the ordinary night-bell, which is constantly ringing as long as the indicator is in a calling position.

From the foregoing it will be clearly understood that by the provision of a device as above described and claimed in connection with the drawings, a very efficient device is provided whereby telephones are thrown into circuit.

Of course it will be distinctly understood that changes may be made in the details of construction and combination of features and elements without in any way departing from the spirit and scope of the invention.

What is claimed as new is—

1. In a switchboard-drop, a magnet, an armature therefor, an oscillating rod movable with said armature and carrying a visual indicator; and means for holding said rod in raised position.
2. In a switchboard-drop, a magnet, an armature therefor, an oscillating rod movable with said armature, and a pivoted support for the free end of said rod.
3. In a switchboard-drop, a magnet, an armature therefor, an oscillatory rod supported by said magnet, and a weighted notched pivoted support for the free end of said rod.
4. In a switchboard-drop, a magnet, an armature therefor, an oscillatory rod movable with the armature and weighted at one end, an indicator carried by the other end of said rod; and a pivoted support for said rod.
5. In a switchboard-drop, a magnet, an armature therefor, an oscillatory rod movable with the armature, an indicator carried by said rod, a socket, and a pivoted support for the free end of said rod, mounted with a portion traversing a passage through said socket when the oscillatory rod is in a raised position.
6. In a switchboard-drop, an electrically-actuated indicator having a rod, a plug-socket, and an oscillatory support for the indicator-rod, having a portion traversing said socket when the indicator is in a raised position.
7. In a switchboard-drop, an oscillatory indicator-rod, a notched pivoted support therefor, and a socket traversed by a portion of said notched support when the indicator-rod is raised.
8. In a switchboard-drop, a magnet, an oscillatory indicator-rod; an armature integral with said rod and supported by said magnet, a spring forming an electrical connection with said rod, and a pivoted oscillatory notched support for the free end of said rod.
9. In a switchboard-drop, a magnet, an armature therefor, a weighted oscillatory indi- 130

cator-rod movable with the armature, a socket, a pivoted notched support for the free end of said rod, and having a portion extending into said socket when the indicator

5 rod is raised, a spring forming an electrical connection with said rod, and electrical connections, as and for the purpose specified.

10. In a switchboard-drop, a magnet, an armature therefor, an oscillatory rod movable with the armature, an indicator carried by said rod, a socket, and a pivoted support for the free end of said rod.

11. In a switchboard-drop, an electrically-actuated indicator having a weighted rod, a plug-socket, and an oscillatory support for 15 the indicator.

In testimony whereof I have hereto affixed my signature in the presence of two witnesses.

GUSTAVUS W. SCHUESSLER.
